UNITED STATES PATENT OFFICE.

LILLON B. BOYCE, OF SYRACUSE, NEW YORK.

SLIDING HINGE.

1,362,837.

Specification of Letters Patent. Patented Dec. 21, 1920.

Application filed September 22, 1920. Serial No. 412,081.

To all whom it may concern:

Be it known that I, LILLON B. BOYCE, a citizen of the United States, residing at Syracuse, in the county of Onondaga and State of New York, have invented a new and Improved Sliding Hinge, of which the following is a specification.

This invention relates to door hinges and it primarily has for its purpose to provide a hinge of the general character stated, of a simple and economical construction in which the hinge members in addition to the usual pivotal connection, are slidably joined whereby the door may be so hung that it has a limited slidable movement relatively to the hinge or pivot connection, so as to provide for readily swinging the door, when open, in a plane at right angles to the hinge post and for easily effecting the opening and closing positions of the said door.

Furthermore, my invention comprehends an improved construction of door hinge that is especially well adapted for use on garage doors, the hinge connection being so designed whereby to permit of sliding the door or doors, when open, part way into the building and for holding such door or doors in position against being blown out or shut.

With other minor objects in view, herein-after apparent, my invention consists of an improved door hinge that embodies the peculiar features of construction and novel arrangement of parts, fully set out in the following detailed description, specifically stated in the appended claims and illustrated in the accompanying drawings, in which:

Figure 1 is a face view of a pair of doors and the framing therefor, with my improved construction of hinges attached.

Fig. 2 is a front elevation of one of the hinges and a portion of a door and the door frame.

Fig. 3 is an edge plan view of the hinge, the several members therefor being at their normal or closed in position.

Fig. 4 is a transverse section of the complete hinge taken on the line 4-4 on Fig. 2.

Fig. 5 is a face view of the back member of the hinge.

Fig. 6 is a cross section thereof.

Fig. 7 is a face view of the slotted central hinge member hereinafter referred to.

Fig. 8 is a cross section.

Figs. 9 and 10 are diagrammatic plan views that show two different positions of a door and its frame or casing joined with my improved hinge connection.

In the practical development of my improved hinge, the same includes a pintle or hinge section 1 that is permanently screwed onto the top jamb or casing and it has the usual knuckles 10 for the hinge or pintle pin 2.

3 designates a front hinge member which is in the nature of a strap iron formed with the usual pintle receiving knuckle 30 at one end and provided near the said end with an inwardly projected stud 31, the purpose of which will presently appear. 70

5 designates, what is hereinafter termed the back hinge member, the same being a flat piece of strap iron, preferably of the same length and thickness of the front hinge member 3 with which it slidably engages, 75 as is clearly shown in Fig. 3, by reference to which it will be observed that the meeting faces of the front and back hinge members 3 and 5 are each formed with longitudinal grooves 12 and 50, the upper and lower 80 edges of which are undercut or dove-tailed, whereby to provide upper and lower dove-tailed trackways α , one-half of each of which is an integral part of the front hinge member and the other half of each of which is an integral part of the other or back hinge member 5, the two opposing grooves 12 and 50, when the back and front hinge members are assembled, constituting a longitudinal housing for receiving a central hinge member 6 that is also in the nature of strap iron of a thickness to provide for a free sliding or extensible movement of the back hinge member and the said center member, relatively to each other and to the front relatively fixedly held hinge iron 3, as will presently be more fully explained. 90

The central hinge member 6 has angled grooves 60-60 in the upper and lower edges, which receive and ride on the upper 100 and lower dove-tailed trackways α - α .

By connecting the back and the front

hinge members and the central hinge members 6 in the manner shown and described, a simple and stable slidable connection of the parts is provided for and at the same time a strong and durable means is developed for holding the front, the back and the central hinge members in proper alignment and against loosening up or rattling.

10 The central hinge member 6 has an elongated slot 61 that extends nearly the full length thereof and into which is received the stud 31 on the inner end of the hinge strap 3 and a similar stud 7 made fast to the back hinge strap 5, near the outer end thereof.

15 The two opposing studs are projected so as to extend but half way across the width of the slot 61 so that they may readily pass each other, when assembling or disconnecting the several hinge members to or from 20 the operative position.

25 The back hinge member 5, when the parts are assembled, is screwed onto the top as indicated in the drawing, it being understood, by referring to Fig. 6, that the means for holding the front hinge member 3 in operative condition against the door is the central hinge member 6.

30 In fitting the hinge, the several members 3, 5 and 6 are assembled on the door and properly attached, the knuckle of the hinge member 3 is fitted between the knuckles 10 of the fixed hinge member 1 and secured by the pintle 2 in the usual way.

35 From the foregoing description taken in connection with the accompanying drawings, the complete construction, the manner of its application and the advantages of my improved hinge will be readily apparent to those skilled in the art to which my invention relates.

40 The arrangement of the parts is such that a very strong and durable hinge is provided that can be economically made and easily applied by any one.

45 The hinge is such that, when opened, the door may be slid back some distance parallel with the front of the door frame or casing, as diagrammatically illustrated in Fig. 9, to provide for a partial closure of the door 50 across the doorway or it may be turned at right angles to the door jamb, as indicated in Fig. 10, the several parts are so connected and held together that, when once assembled, they cannot become disconnected or in 55 any manner disarranged.

What I claim is:

1. A hinge of the character stated comprising in combination with a pintle carrying member; an outer strap member having a pintle receiving knuckle, a back strap member attachable to a door and a central strap member, the latter having a slot extending lengthwise thereof, the inner and the outer strap members each having a stud 65 that projects into the slotway of the central

strap member and means for holding the inner and outer and the central hinge members in slidable connection.

2. A hinge of the character stated comprising in combination with a pintle carrying member; an outer strap member having a pintle receiving knuckle, a back strap member attachable to a door and a central strap member, the latter having a slot extending lengthwise thereof, the inner and 70 the outer strap members each having a stud that projects into the slotway of the central strap member and means for holding the inner and outer and the central hinge members in slidable connection, the studs of 80 the inner and outer members being partly projected within the slotway of the central member, whereby to permit the inner and outer members sliding endwise free of each other, when the front member is disconnected from the fixed or pintle member of 85 the hinge.

3. A hinge of the character stated, comprising in combination with a pintle carrying member; an outer strap member having a pintle receiving knuckle, a back strap member and a central strap member, the latter being located between the front and back members and means for holding the several 90 strap members in slidable connection.

4. A hinge of the character stated, comprising in combination with a pintle carrying member, an outer strap member having a pintle receiving knuckle, a back member adapted for being attached to the door, the 100 opposing faces of the outer and back members being held in slidable contact, the said opposing faces each being longitudinally grooved, the upper and lower edges of said 105 grooves being undercut whereby, when the two members are assembled, a longitudinal chamber is provided between the front and back members and having top and bottom centrally disposed longitudinal dove-tailed tracks, and a central hinge member that 110 slidably fits in the said longitudinal chamber, its upper and lower edges each having a V-shaped groove for engaging the upper and lower dove-tailed trackways and thereby 115 lock the inner and outer hinge members in slidable engagement.

5. A hinge of the character stated comprising in combination with a pintle carrying member, an outer strap member having a pintle receiving knuckle, a back member 120 adapted for being attached to the door, the opposing faces of the outer and back members being held in slidable contact, the said opposing faces each being longitudinally grooved, the upper and lower edges of said 125 grooves being undercut whereby, when the two members are assembled, a longitudinal chamber is provided between the front and back members and having top and bottom centrally disposed longitudinal dove-tailed 130

tracks, and a central hinge member that slidably fits in the said longitudinal chamber, its upper and lower edges each having a V-shaped groove for engaging the upper and lower dove-tailed trackways and thereby lock the inner and outer hinge members in slidable engagement, the outer hinge member having an inwardly extending stud

near its inner end that projects into the slot of the central hinge member, the back hinge member being provided with a stud near its outer end that projects into the slot of the central member and opposes the other stud.

LILLON B. BOYCE.
